Des. 179,559
Patented Jan. 22, 1957

179,559

TRAILER

Patrick J. Chisholm, Hickman Mills, Mo., assignor to Keystone Trailer & Equipment Co., Inc., Kansas City,
Mo., a corporation of Missouri

Application October 8, 1954, Serial No. 32,596

Term of patent 14 years

(Cl. D14—3)

Fig. 1 is a perspective view of a trailer showing my design.

Fig. 2 is a side elevational view thereof.

Fig. 3 is a front elevational view thereof.

The dominant feature in the design resides in the front end panel of the trailer, which front end panel is shown in full lines.

I claim:

The ornamental design for a trailer, as shown and described.
